UNITED STATES PATENT OFFICE.

EDWARD H. BICKFORD, OF TORONTO, ONTARIO, CANADA.

DESIGN FOR A FOOTBOARD-REGISTER FOR MOTOR-CARS.

43,663.

Specification for Design.

Patented Mar. 4, 1913.

Application filed December 19, 1912. Serial No. 737,738. Term of patent 7 years.

To all whom it may concern:

Be it known that I, EDWARD HASTINGS BICKFORD, a subject of the King of Great Britain, and resident of the city of Toronto, county of York, Province of Ontario, in the Dominion of Canada, have invented a new, original, and ornamental Design for a Foot-board-Register for Motor-Cars, of which the following is a specification.

The drawing represents a perspective view of my foot plate register and air directing baffle.

The design consists of a long narrow grilled or perforated plate designed to form a portion of the foot board of a motor car. The plate is substantially right angular in

cross section having a depending flange at the lower edge which extends downwardly forming a baffle plate for directing air currents upwardly through the holes in the plate.

What I claim is:—

The ornamental design for a foot board register for motor cars as shown and described.

Signed at the city of Toronto, county of York, Province of Ontario, in the Dominion of Canada, this 14th day of December 1912.

EDWARD H. BICKFORD.
